AU 291 EX
OR D 15,022

No. 15,022

May 27- 1884.

AF 5

UNITED STATES PATENT OFFICE.

AARON J. NELLIS, OF PITTSBURG, PENNSYLVANIA.

DESIGN FOR A MONUMENT.

SPECIFICATION forming part of Design No. 15,022, dated May 27, 1884.

Application filed March 31, 1884. Term of patent 14 years.

To all whom it may concern:

Be it known that I, AARON J. NELLIS, a citizen of the United States, residing at Pittsburg, in the county of Allegheny and State of Pennsylvania, have invented and produced a new and original Design for Monuments, of which the following is a specification, reference being had to the accompanying photograph, forming a part thereof, and which represents the monument in perspective elevation.

The characteristic feature of the design is the globe or sphere, which, being a body whose surface is at all points equidistant from its center, is indicative of perfect symmetry. The sphere forms the body of the monument and rests upon a flat rectangular base. Encircling the sphere is a scarf intended to receive an inscription. The pedestal is rectangular and of little height, so as to give special prominence to the sphere, though any height of pedestal which will not dwarf the sphere may be substituted.

In the photograph, A indicates the pedestal, which may be finished with molded edges a.

B indicates the globe or sphere, and b the scarf encircling the globe.

The base A may be of granite, while the sphere is of marble; but the material forms no part of the design.

Having thus described my design, what I claim, and desire to secure by Letters Patent, is—

1. As a design for monuments, a sphere resting on a flat rectangular pedestal having the vertical sides A and the inwardly-inclined top moldings, a a, as shown and described.

2. A design for monuments, consisting of a sphere encircled by a scarf, and resting on a flat rectangular pedestal having the vertical sides A and the inwardly-inclined top moldings, a a, as shown and described.

In testimony whereof I affix my signature, in presence of two witnesses, this 13th day of March, 1884.

AARON J. NELLIS.
